(57) **CLAIM**

The ornamental design for the "fluid distribution nozzle", as shown and described.

DESCRIPTION

FIG. 1 is a perspective view of the nozzle from the rear;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a plan view thereof, taken from above; and,

FIG. 7 is plan view thereof, taken from below.

The model relates to a nozzle for dispensing fluids which has a central body with rounded lines that converge towards the dispensation mouth.
